United States Patent Office

Des. 180,942
Patented Sept. 10, 1957

180,942

HAT

Delfin Florido, Bronx, N. Y., assignor to Darrol Company,
New York, N. Y.

Application August 15, 1956, Serial No. 42,607

Term of patent 14 years

(Cl. D3—13)

FIG. 1.

FIG. 2.

FIG. 3.

Fig. 1 is a top plan view of a hat showing my new design;

Fig. 2 is a front elevational view; and

Fig. 3 is a side elevational view thereof.

I claim:

The ornamental design for a hat, substantially as shown.
